UNITED STATES PATENT OFFICE.

ALBERT W. PARKES, OF DUNDAS, ONTARIO, CANADA, ASSIGNOR TO NILES-BEMENT-POND COMPANY, OF NEW YORK, N. Y., A CORPORATION OF NEW JERSEY.

SLOTTING MACHINE.

Application filed January 16, 1924. Serial No. 686,559.

This invention relates to slotters and like machines having a work support and a reciprocating tool slide adapted to operate on work carried by the work support. The work support ordinarily comprises a movable saddle carrying a slide thereon in turn supporting a rotary work table and means is provided for intermittently feeding these three members in timed relation to the tool slide reciprocation. Other means is provided for continuously traversing the said work supporting members. The primary object of the invention is to provide an improved slotter of this type. Another object of the invention is to provide interlocking means between the feeding and traversing means for preventing the simultaneous operative engagement thereof with the work supporting members.

The tool slide can be operated from any convenient source of power and, in the drawings, I have illustrated the same as operated by an electric motor. Another object of the invention is to provide an improved driving connection between this motor and the tool slide, such connection including change speed gearing and a clutch and improved operating means therefor including an interlocking mechanism permitting the shifting of the gears only when the clutch is in the disengaged position.

With the above and other objects in view, my invention consists in the features of construction and operation set forth in the following specification and illustrated in the accompanying drawings. In such drawings annexed hereto and forming a part of this specification, I have shown my invention embodied in a vertical crank slotter but it will be understood that the invention can be otherwise embodied and that the drawings are not to be construed as defining or limiting the scope of the invention, the claims appended to this specification being relied upon for that purpose.

Referring to the figures of the drawings: Figure 1 is a front elevation of a vertical crank slotter embodying my invention.

Fig. 2 is a rear end elevation thereof taken from the right-hand side of Fig. 1.

Fig. 3 is a fragmentary rear view showing the work support.

Fig. 4 is an enlarged fragmentary sectional view of the main driving mechanism.

Fig. 5 is an end elevation thereof. 55

Fig. 6 is a fragmentary sectional view taken on line 6-6 of Fig. 11.

Fig. 7 is a fragmentary plan view of the feeding and traversing mechanism.

Fig. 8 is a horizontal sectional view 60 through Fig. 7.

Fig. 9 is a front elevation of Figs. 7 and 8.

Fig. 10 is a plan view, partially in section, of the work support and its operating mechanism. 65

Fig. 11 is an enlarged fragmentary front elevation of the gear shifting mechanism.

Fig. 12 is a sectional view taken on line 12-12 of Fig. 4.

In the drawings, 1 indicates the bed and 2 the upright or column of a vertical crank slotter. A tool slide 3 counterbalanced at 4 is guided for vertical reciprocation in the column. The tool slide is reciprocated by crank mechanism 5 operated from a motor 6 through driving mechanism hereinafter described. A work support 7 is mounted on the bed beneath the tool slide. 70

A gear 8 on the crank shaft 9 is driven from the motor pinion 10 through the following mechanism: The motor pinion 10 meshes with a gear 11 loose on a bearing 12 for a shaft 13. A clutch 14 splined to the shaft 13 is adapted to engage the gear with the shaft. The portion 14^a of the clutch can

be shifted by means of a yoke 15 on a shaft 16. Movement of the clutch and yoke in one direction is adapted to engage the clutch and movement thereof in the opposite direction is adapted to apply a friction brake at 17. 80

Two shafts 18 and 19 are mounted in the gear box parallel with the shaft 13. A pair of gears 20 and 21 splined to the shaft 13 are adapted to mesh respectively with gears 22 and 23 on the shaft 18. A second pair of gears 24 and 25 splined to the shaft 13 are adapted to be meshed respectively with gears 26 and 27 on the shaft 18. A pair of gears 28 and 29 splined to the shaft 19 are adapted to be meshed respectively with gears 30 and 31 on the shaft 18. A pinion 32 on the shaft 19 is in mesh with the gear 8 on the crank shaft. Eight driving speeds can be obtained by shifting the gearing just described. 90

The gears 24 and 25 can be shifted by means of a handle 33 on a shaft 34 carrying a yoke 35 engaging the said gears. The gears 28 and 29 can be shifted by means of

a handle 36 on a shaft 37 carrying a yoke 38 engaging such gears. The gears 20 and 21 can be shifted by means of a handle 39 on a shaft 40, a rod 41 operatively connecting an arm 42 on the shaft 40 with a yoke 42 engaging such gears. A latch 43 is provided on each handle for holding the gears in their shifted positions. Each of shafts 34, 37 and 40 carries a disk-like member 44 provided with three notches *a*, *b* and *c*. Three notches of each disk are adapted to be engaged by lateral projections 45 on three arms radiating from a member 46 mounted on a shaft 47. An arm 48 on the shaft 47 is operatively connected by means of a rod 49 to an arm 50 on the clutch shifting shaft 16. A rod 51 operatively connects the arm 48 to an operating handle 52 on the column adjacent the operator's usual position at the machine. The arrangement of the parts is such that when the clutch is in the driving position (to the left, Fig. 4), the projections 45 are engaged in certain of the notches *a*, *b* and *c*. Therefore, the gears cannot be shifted until the clutch is disengaged, such clutch disengaging action rotating the shaft 47 clockwise (Fig. 11) and withdrawing the projections 45 from the notches.

The work support comprises a saddle 53 slidable longitudinally on ways 54 of the bed 1, a slide 55 transversely slidable on ways 56 of the saddle, and a work table 57 rotatably mounted on the slide. The saddle and slide are moved respectively by means of screws 58 and 59. The table is rotated from a shaft 60 having a worm 61 splined thereto and meshing with a worm wheel 62 on the work table. The screw shaft 59 and shaft 60 extend rearwardly parallel with the ways 56 on the saddle into a gear box 63 mounted on the saddle. The forward ends of shafts 59 and 60 are squared at 59^a and 60^a respectively whereby the same can be rotated by hand for fine adjustments. Shaft 59 may also be rotated from the squared ends of a shaft 59^b connected to shaft 59 through spiral gears 59^c. Gears 64 and 65, driven from a gear 66 on a shaft 67, are loosely mounted respectively on shafts 59 and 60 within the gear box. Clutches 68 and 69 splined to shafts 59 and 60 are adapted to operatively connect either gear with its shaft. A yoke 70 engaging the clutches at its ends and pivoted at 71 is adapted to be operated by a clutch rod 72 pivoted to one end of the yoke at 73 and extending to the front of the machine whereby either shaft 59 or 60 may be thrown into operation to move the slide and rotate the table respectively. The shaft 67 carries a bevel gear 74 at its inner end which meshes with a like gear 75 splined to a shaft 76. Shaft 67 and gears 74 and 75 are rotatably supported on the saddle and move therewith along the shaft 76. This mechanism is described and

claimed in patent to W. J. Hagman No. 1,528,150 granted March 3, 1925.

The feeding of the work supporting elements is preferably accomplished from the tool operating means as follows: A shaft 77 is oscillated from a cam 78 on shaft 9 through a lever 79 mounted on one end of the shaft and engaging the cam. A second lever 80 on the forward end of shaft 77 is operatively connected by a link 81 to a disc 82. The disc 82 is loosely mounted on a shaft 83 directly adjacent a gear 84 also loose thereon. A double pawl 85 pivoted to the disc is adapted to engage the gear 84 and intermittently drive the same in either direction as will be understood. The pawl can be shifted on its pivot to either driving position by means of a handle 86. The shaft 83 is operatively connected to the shaft 76 through bevel gears 87 and 88 secured to such shafts respectively. A shaft 89 parallel with the shaft 83 is operatively connected to the saddle screw 58 by a pair of bevel gears 90. A gear 91 splined to the shaft 89 is adapted by means of a rod 92 and a clutch yoke 92^a to be shifted into and out of mesh with a gear 93 keyed to the shaft 83. A clutch 94 splined to the shaft 83 is adapted to operatively connect the gear 84 to such shaft. A spring 95 normally engages this clutch and the same is adapted to be disengaged in the manner hereinafter described, by means of a rod 96 having a clutch yoke 96^a engaging the clutch.

The operation of the feed mechanism is as follows: To feed the saddle 53, the gear 91 is placed in mesh with the gear 93, the clutch 94 being normally engaged with the gear 84 by means of spring 95. If the slide 55 and table 57 are not to be fed, the clutches 68 and 69 are placed in the neutral position as shown in Fig. 10. The oscillation of the disc 82 will thereupon be transmitted to the screw 58 to intermittently feed the saddle. When it is desired to feed the slide 55 or to rotate the table 57, the gear 91 is disengaged from the gear 93. The oscillations of the disc 82 are transmitted through the shaft 76 and the other mechanism described to the gears 64 and 65 on the screw shaft 59 and table operating shaft 60. The clutch yoke 70 may be operated from the rod 72 to engage either clutch 68 or 69 with its gear and thereby drive either the screw shaft 59 or shaft 60 as desired. The slide is thereby fed along its ways and the table rotated from these shafts as will be understood.

Means is provided in connection with the mechanism just described for continuously operating the saddle, slide and table shafts to effect traversing movement of the saddle, slide and table. I have illustrated a motor 97 for performing this function. A pinion 98 on the motor shaft meshes with a gear 99

keyed to a shaft 100 adjacent and in axial alinement with the shaft 76. A bevel gear 101 loose on the shaft 100 is in mesh with the bevel gear 87 and a clutch 102 splined to the shaft 100 between bevel gears 88 and 101 is adapted to operatively connect the shaft 100 to either of such gears. The clutch 102 is engaged by a clutch shifting yoke 103 on a vertical shaft 104. The clutch 102 can be shifted by means of a rod 105 engaging an arm 106 on the shaft and extending to the front of the machine.

It will be noted that both the feeding and traversing of the work supporting members are accomplished through the same driving elements. The following mechanism provides an interlock preventing the simultaneous engagement of the feeding and traversing means with such elements. The rear end of the clutch shifting rod 96 is connected to a lever 107 pivoted at 108. The intermediate portion of this lever carries a roller 109 engaging the end of an arm 110 secured to the vertical clutch shifting shaft 104. When the clutch 102 is in the neutral position, the roller 109 engages in a notch 111 in the arm 110 and the feed clutch 94 is engaged with the gear 84. Movement of the rod 105 to engage the clutch 102 with either of bevel gears 88 and 101 cannot take place without forcing the roller 109 from the notch 111 and thereby disengaging the feed clutch 94. It will therefore be seen that the feed clutch 94 and the traversing clutch 102 cannot be in driving engagement simultaneously. The feed clutch 94 is normally held in engagement by the spring 95 and the engagement of the traversing clutch 102 automatically disengages the feed clutch 94 against the action of the spring.

What I claim is:

1. In a slotter, the combination of a base, a work support and a tool slide on the base, power operated means for reciprocating the tool slide, mechanism for intermittently feeding the work support synchronously with the said reciprocation, a clutch for disengaging the feeding means, power operated means including a pair of bevel gears and a clutch therebetween for continuously traversing the work support in either direction, and interlocking means preventing the simultaneous engagement of the clutches.

2. In a slotter, the combination of a base, a work support and a tool slide on the base, power operated means for reciprocating the tool slide, mechanism for intermittently feeding the work support synchronously with the said reciprocation, a clutch for disengaging the feeding means, a spring normally operative to engage the clutch, power operated means including a clutch for continuously traversing the work support in either direction, means for shifting the last named clutch, and means automatically oper-

ative to disengage the feeding clutch when engaging the traversing clutch.

3. In a slotter, the combination of a base, a work support and a tool slide on the base, power operated means for reciprocating the tool slide, a shaft in the base, mechanism including a ratchet gear on the shaft for intermittently feeding the work support synchronously with the said reciprocation, a clutch for disengaging the ratchet gear from the shaft, a bevel gear on the shaft, a relatively right angular shaft, a pair of bevel gears loose thereon and in mesh with the said bevel gears, a clutch splined to the shaft between the said pair of bevel gears, a shifter for engaging the clutch with either bevel gear, and an interlock for preventing the simultaneous engagement of the clutches.

4. In a slotter, the combination of a base, a saddle longitudinally slidable thereon, a slide transversely slidable on the saddle, a work table rotatable on the slide, a tool support on the base, power operated means for reciprocating the tool support, mechanism for intermittently and selectively feeding the saddle, slide and table synchronously with the said reciprocation, power operated means for continuously and selectively traversing the saddle, slide and table, and interlocking means preventing the simultaneous engagement of the feeding and traversing means.

5. In a slotter, the combination of a base, a saddle longitudinally slidable thereon, a slide transversely slidable on the saddle, a work table rotatable on the slide, a tool support on the base, power operated means for reciprocating the tool support, a shaft in the base, mechanism for intermittently rotating the shaft synchronously with the said reciprocation for feeding, a shaft parallel with the first named shaft and operatively connected to the saddle to move the same, means providing an operative connection between the two shafts, a shaft at right angles to the first named shaft and operatively connected thereto, means providing an operative connection between the third named shaft and the slide and table for moving the same, means for continuously rotating the first named shaft for selectively traversing the saddle, slide and table, and interlocking means preventing the simultaneous engagement of the feeding and traversing means.

6. In a slotter, the combination of a base, a work support and a tool slide on the base, power operated means for reciprocating the tool slide, a feed shaft operatively connected to the work support, mechanism for intermittently rotating the feed shaft to move the work support synchronously with the said reciprocation, a bevel gear on the feed shaft, a shaft at right angles to the feed shaft, a pair of bevel gears loose thereon and in mesh with the first named bevel gear, a motor operatively connected to the second

named shaft, a clutch splined to such shaft between the pair of bevel gears thereon, and means for engaging the clutch with either of said bevel gears, whereby said work support can be continuously traversed in opposite directions.

7. In a slotter, the combination of a base, a work support thereon, a column on the base, a tool slide on the column over the work support, a power element, an operative connection including change speed gearing and a clutch between the power element and the slide for reciprocating the latter, means for shifting the change speed gearing, means for shifting the clutch, and interlocking mechanism between the said means for permitting shifting of the gears only when the clutch is disengaged.

8. In a slotter, the combination of a base, a work support thereon, a column on the base, a tool slide on the column over the work support, a power element, an operative connection including change speed gearing and a clutch between the power element and the slide for reciprocating the latter, the said change speed gearing including three pairs of sliding gears, three shifters for respectively sliding the said three pairs of gears, means for shifting the clutch, and interlocking mechanism between the

three shifters and the said means for permitting shifting of the gears only when the clutch is disengaged.

9. In a slotter, the combination of a base, a work support thereon, a column on the base, a tool slide on the column over the work support, a motor mounted on the machine, an operative connection between the motor and the slide for reciprocating the latter, means for intermittently feeding the work support from the motor, a motor for continuously traversing the work support, and means preventing the simultaneous operation of both motors on the work support.

10. In a slotter, the combination of a base, a work support thereon, a column on the base, a tool slide on the column over the work support, means for intermittently feeding the work support, change speed gearing and a clutch in said intermittent feeding means, a motor for continuously traversing the work support, means preventing the simultaneous operation of said intermittent feeding and continuous traversing means, and interlocking mechanism permitting the shifting of said change gearing only when the clutch is disengaged.

In testimony whereof, I hereto affix my signature.

ALBERT W. PARKES.
